UNITED STATES PATENT OFFICE.

BRYAN I. DAY, OF FORT MADISON, IOWA.

DESIGN FOR A TOY ANIMAL.

Application filed August 13, 1923. Serial No. 7,001. Term of patent 7 years.

To all whom it may concern:

Be it known that I, BRYAN IRVIN DAY, a citizen of the United States, residing at Fort Madison, county of Lee, and State of Iowa, have invented a new, original, and ornamental Design for a Toy Animal, of which the following is a specification, reference being had to the accompanying drawing, forming part thereof.

I claim—

The ornamental design for a toy animal as shown.

Ft. Madison, Iowa, August 3d, 1923.
